UNITED STATES PATENT OFFICE.

GEORGE J. KENNEDY, OF BALTIMORE, MARYLAND.

PUMP.

SPECIFICATION forming part of Letters Patent No. 741,045, dated October 13, 1903.

Application filed January 16, 1902. Serial No. 90,088. (No model.)

To all whom it may concern:

Be it known that I, GEORGE J. KENNEDY, a citizen of the United States, residing at Baltimore, in the State of Maryland, have invented 5 certain new and useful Improvements in Pumps; and I do hereby declare the following to be a full, clear, and exact description of the invention, such as will enable others skilled in the art to which it appertains to make and use the same.

My invention relates to certain improvements in pumps, more particularly such as are adapted to be actuated by steam or air, usually termed "steam-vacuum" pumps, for 15 forcing or elevating liquids to desired altitudes, which is the special design of my invention.

The objects of my invention are, among other things, to provide for the arrangement or 20 location of the pump-actuating mechanism at a readily-accessible or convenient point with relation to the motor or engine, while the pump itself may be located in the bottom of a well or excavation, for instance, for service. 25 Also, it provides for greatly simplifying the construction and operation of the parts—as, for example, controlling the exhaust of the steam-pressure from the water-receiving chamber—also, the controlling of the vacuum-producing water-spray to said water-chamber, together with the delivering of the steam or 30 air pressure into the last named, all by a common valve mechanism. It also provides for regulating the throw of the steam or air pressure valve according to the amount of water-supply required and for promoting the utility 35 of the pump generally.

The nature of my invention consists in the combination and arrangement of parts, including their construction, substantially as 40 hereinafter more fully disclosed, and specifically pointed out in the claims.

In the accompanying drawings, forming a part of this application and illustrating the 45 preferred embodiment of my invention, Figure 1 is a sectional elevation. Fig. 2 is an enlarged detail section showing more especially the valve mechanism as adapted for a double-acting pump. Fig. 3 is a sectional 50 elevation showing the pump double-acting, the water-receiving chamber, valve mechanism, vacuum-producing spray-pipe, &c., being duplicated. Fig. 4 is a modification show-

ing the pump double-acting, with the power-cylinders, having pistons actuating the steam 55 or air pressure supply valve, receiving their steam or air supply from the duplicate water-receiving chambers, &c. Fig. 5 is also a sectional elevation of a further modification, also showing the pump double-acting, with 60 the water-spraying vacuum-producing pipes supplied from the duplicate water-receiving chambers, &c. Figs. 6, 7, 8, and 9 are views of a still further modification disclosing a single valve-easing and a single valve comprising 65 the valve mechanism.

It will be understood that I do not limit myself to details, as they may be varied as circumstances suggest without departing from the spirit of my invention and the same 70 yet remain intact and be protected.

In carrying out my invention I employ for receiving the water or liquid to be raised or lifted a chamber 1, sufficiently elevated in any suitable way in the bottom of a well or excavation—for instance, to freely admit the water or liquid thereto through a valved opening or port 1^a in its receiving end or bottom. Said chamber has, as usual, a water or liquid discharging pipe 1^b connected or communicating therewith near its receiving end or bottom and extending upwardly to any required height, according to the altitude of the point of delivery, as will be readily appreciated. Within said discharge or delivery 85 pipe is arranged or seated near its receiving end a ball-valve 1^c, opening or unseating upwardly for the ingress of the liquid and oppositely seating or closing to prevent the return of said liquid after its influx. 90

An air or steam supply valve 2 is shown arranged at the upper or top end of the chamber 1 with its casing or chamber 2^x secured to the last named and having a delivery-port 2^a communicating therewith. Said valve-casing has a reduced pipe-like extension 2^b at its upper or one end, adapted to suitably connect or communicate with the steam or air source of supply or engine, eligibly located. Said valve as it is reciprocated upon its seat is adapted to open and close the steam or air port 2^c, exhausting through itself at 2^x and the port 2^d of said valve-casing into a subchamber 2^e of said casing, whence the exhaust-steam passes through a port 2^f into 105 the outlet or vent pipe 2^g to the air. Said 100

supply-valve 2 has its rod or stem 2^{aa} extended through the upper end of its casing considerably beyond the same, as shown, for a purpose presently seen. A second valve 3 is arranged above and contiguously to the valve 2 and carried by said extension of the stem or rod 2^{aa} of the valve 2, with its casing or closure secured to the part 2^b for conveniently supporting the same. Connecting or 10 communicating with the chamber of the valve 3 are two pipes 4^a, also communicating or connecting with the water-delivery pipe 1 and the water-receiving chambers 1, respectively. The pipe 4 has a valve 4^{aa} for regulating the amount of flow of water therethrough, and the pipe 4^a extends downwardly into the water-receiving chamber 1 and is turned or curved upwardly therein goose-neck fashion. Said pipe 4^a has its upturned 15 lower end in the water-receiving chamber provided with a foraminous closure, nozzle, or rose 4^{bb} to effect the discharge or delivery of the water passing therethrough into said chamber in the form of a spray to produce 20 after the delivery of steam or air pressure into said chamber and the cutting off said pressure, as presently explained, a vacuum to effect, with the aid of atmospheric pressure, the lifting or feeding of the water from below 25 into the water-receiving chamber. The valve 3 is adapted, having ports 4^x 4^{xx}, to establish communication therebetween and the pipes 4^a by the movement of the valve 2, whose stem or rod carries said valve 3, when the last- 30 named is closed or the steam or air pressure is cut off from the water-receiving chamber, and thus provide for the delivery of water from the discharge-pipe 1^b of the chamber 1 via the pipe 4, the ports of valve 3, and pipe 4^a into said water-receiving chamber. Simultaneously with this action of parts the expanded steam or air pressure will be exhausted from said water-receiving chamber via the exhaust passage or port of the valve 4^a 45 into said water-receiving chamber. Then registering with the exhaust-port of its chamber, delivering into the exhaust-outlet 2^h. Said pipe 4 has a hand-actuated valve 4^{aa} to provide for regulating the amount of flow of water therethrough, and accordingly 50 the size or extent of the water spray issuing from the pipe 4^a. A power-cylinder 5, also suitably supported or secured for convenience upon the part 2^b contiguously to the valve 3, has its piston 5^a secured to and carried by the valve-rod extension of the valve 2, said cylinder 5 being provided with a slide-valve 6 of the usual or approved construction, with its housing or containing chamber or chest suitably ported and connected up 55 with the steam or air pressure supply for actuating the piston 5^a. Said slide-valve as commonly arranged has its stem 5^b connected to one end of a lever 5^c, suitably supported in position. The other end of said lever is 60 actuated by the rod or stem 2^a, carrying the piston 5, in such manner that said slide-valve and piston will be oppositely reciprocated,

and thus provide for admitting steam or air pressure to said piston and exhausting the same alternately, as well understood. Any 70 suitable means may be provided for actuating the lever 5^c from the piston-rod, preferably as shown, said lever being forked or bifurcated, as at 7, and having the arms or branches thereof riding upon or receiving the 75 ends of a transverse pin 7^a, carried by said rod. A second piston or valve 8 is secured to the valve-rod or stem extension 2^{aa}, with its chamber or casing 8^a for convenience secured or supported upon the part 2^b and 80 adapted to contain a quantity of oil or air pressure for regulating the throw or speed of the steam or air pressure supply valve for the water or lifting chamber. Said valve chamber or casing 8^a is supplied with a by-pass or pipe 8^b, connecting with and establishing communication between the opposite ends of said chamber to deliver the oil or air pressure in front of the piston 8 during the performance of its strokes. Said by-pass or 85 pipe 8^b is equipped with a hand-actuated valve 8^c for varying the extent of the flow or passage of the oil or air pressure therethrough from end to end of the valve-chamber 8^a as the liquid or fluid is set in motion by the action of the piston 8 of the valve 8^c. It will 90 therefore be observed that under some circumstances it is required or desirable that the lifting action of the water receiving or lifting chamber shall be such that the filling 95 thereof be quite slow—say, restricted to once a minute. In order to compass this, it is only necessary to vary the turning or adjusting of the valve 8^c the required degree, which will consequently lessen the amount of flow of the 100 oil or air pressure via said by-pass and will of course retard the displacement of such liquid or fluid in front of the piston 8^a, accordingly effecting the movement of the valve 5^a and the time required to effect the lifting 105 of the water into and the filling of the water-receiving chamber. 110 In the modification disclosed by Fig. 4, showing the pump as double-acting, I employ an additional, preferably valved, pipe 4^b for supplying water from the discharge or delivery pipe 1^b to the chamber of the valve 3, also an additional water-spraying or vacuum-producing pipe 4^c, dipping into a second water-receiving chamber 1^d and having connection 115 also with the chamber of the valve 3. The valve 2 also has its chamber provided with a second steam or air pressure delivering pipe 2^l, connecting with said second water-receiving chamber 1^d. Communication, it will be 120 observed, is established between the pipes 4^b and 4^c to produce a vacuum in said second water-receiving chamber alternately with establishing communication between the pipes 4 and 4^a, producing a vacuum in the first-referred-to water-receiving chamber after the 125 delivering of steam or air pressure into the second water-receiving chamber 1^d and the cutting off of said pressure from said chamber. 130

ber. Simultaneously with the delivering of the water spray into said second water-receiving chamber the steam or air pressure supply valve 2 will be exhausting, via its exhaust-port 2^{xx}, pipe 2¹, and pipe 2^h, the exhausted steam, &c., from said second water-receiving chamber, the inlet-valve of the last named then opening and permitting the lifting of the water into said chamber. Upon the closing off of the water spray said inlet-valve of said chamber will automatically close and the inlet-valve of the discharge-pipe of said chamber be opened by the pressure of the inflowing water, when upon again admitting steam or air pressure to said chamber the water therein will be forced out through said discharge-pipe, and by the continued alternate repetition of the aforesaid operation of parts both water-receiving chambers will be supplied with water and combined to double the lifting or discharging capacity of the pump.

In the modification as disclosed in Fig. 5, which also shows the pump as double-acting, I also employ two water-receiving chambers 1^e 1^f, having each a discharge or delivery pipe 2^{bb} 2^{cc}, respectively. Said chambers are provided at their lower ends preferably with pendent inlet-pipes 9 9^a, containing upwardly-opening ball-valves 9^b 9^c, and said delivery or discharge pipes are equipped with similar valves 9^d 9^e, also opening upwardly, the action and function of which are the same as the corresponding parts of the forms of the pump heretofore shown and described. At the upper ends preferably of said chambers is arranged a valve 10, contained in a chamber 10^a, fixed to the said ends of the first-referred-to chambers, having a suitable supply-pipe connection 11 with the head or source of steam or air pressure. Said valve 10 has a central exhaust-port 10^b and two water-feeding ports 10^c 10^d in its face, said port 10^b being adapted to alternately establish communication between the atmosphere and the exhaust-steam ports 12 12^a of the two water-chambers 1^e 1^f by the movement of said valve. Said ports 10^c also by the movement of said valve are adapted to alternately effect communication with water-ports 13 13^a, having pipe connections 13^b 13^c with the discharge or delivery pipes 2^{bb} 2^{cc}. Said ports 10^c 10^d are further adapted, by the action of the same valve, to alternately establish communication with the ports 13 13^a, connecting with the water-pipes 13^c 13^d, and the water-spraying pipes 14 14^a, depending in the two water-receiving chambers 1^e 1^f, as shown, to alternately produce the vacuum in said chambers for the lifting of the water thereinto. Steam or air pressure is alternately supplied or delivered into the water-chambers 1^e 1^f from the chamber 10^a via, preferably, inverted-T-shaped perforated pipes 15 15^a, depending a suitable distance into said water-receiving chamber, said supply or delivery of steam or air pressure being controlled by the valve 10, as seen. Said valve has suitably secured to it, about centrally of its upper side, a stem or rod 10^e, passing, preferably, through a short upward extension or shoulder 10^f of said valve, adapted, as the valve is moved or reciprocated, to play between two cross-pieces or stops 10^g, secured or arranged within the chamber 10^a to limit the throw or movement of said valve. Said stem or rod 10^e extends into two aligned power-cylinders 16 16^a, one secured at each end of the casing or chamber 10^a, but not communicating therewith any further than having openings in their inner ends or heads for the passage therethrough of said rod or stem. This stem or rod has secured to it and carries two pistons 10^h 10ⁱ, one arranged in each of the cylinders 16 16^a to alternately receive the impact of steam or air pressure supplied to said cylinders. The cylinders 16 16^a are alternately supplied with steam or air pressure via the water-receiving chambers 1^e 1^f and pipes 17 17^a, effecting communication between said cylinders and said water-receiving chambers. Said steam or air pressure supply for said cylinders 16 16^a, which initially enters the valve-chamber 10^a, thence passing into the water-receiving chambers 1^e 1^f, thus, after producing a vacuum in the last-named chambers for aiding the lifting of the water thereinto, also drives the pistons which actuate the valve controlling such steam or air pressure supply to said water-receiving chambers, the pressure-exhausting action in said chambers, and the supplying of the water spray into said chambers. The speed of the valve mechanism or the throw of the piston in this example of the disclosure of the principles of my invention is regulated or controlled from the boiler in the engine-room.

In the modification of my invention as disclosed by Fig. 6, also of the double-acting type, I employ also two water-receiving chambers 1^g 1^h, differing somewhat from the last form described. Also applied to the discharge or delivery pipes 3^{aa} 3^{bb} are two water-spraying pipes 4^{aa} 4^{bb} for producing the vacuum, although not communicating with said discharge-pipes. Said water-spraying pipes have their lower or receiving ends communicating with the opposite water-receiving chambers, thus providing, as the inlet and check valves 3^c 3^{cc} 3^d 3^{dd} of said chambers and their delivery-pipes are actuated, for alternate filling and emptying the said chambers for the corresponding or alternate spraying of the water from said pipes 1^g 1^h in opposite water-receiving chambers, as will be readily appreciated. At the upper end of the water-receiving chambers 1^g 1^h is arranged a preferably cylindric valve 18, having a central exhaust-port 18^a, adapted, as the valve is reciprocated, to alternately establish communication via the ports 19 19^a in the upper ends of the water-receiving chambers 1^g 1^h with said chambers and the atmosphere. The chamber 18^b, containing the valve 18, has

steam or air pressure ports 18^c 18^d in communication with the water-receiving chambers 1^g 1^h via spraying-pipes 19 19^a, preferably of inverted -T shape, and depending in said 5 chambers for delivering, as in the last-referred-to modification, the steam or air pressure thereinto. These ports 18^c 18^d are alternately opened and closed by the valve 18 for the purpose aforesaid, and the valve-chamber 18^b is supplied with air-pressure or steam by pipe, as at 18^x, leading to the supply of such liquid or fluid, said pipe connecting with one end of said chamber. A suitable piston-valve 19, whose stem is fixed to the cylindric 15 valve 18, actuates the last named, said valve 19 having its chamber 19^x suitably ported and receiving steam or air pressure from the pipe 18^x via an intermediate pipe 19^a, said intermediate pipe 19^a also communicating 20 with the ends of the chamber 18^b of the valve 18, as shown. The speed of this valve mechanism or the throw of the piston is also regulated, as in the last-described modification, from the boiler in the engine-room.

25 In the modification as disclosed by Fig. 7 I arrange upon or in connection with the casing of the water receiving or lifting chamber 1 a valve mechanism applicable for either a single chamber or duplicate chambers, as in 30 a single-acting or a double-acting pump. Said valve mechanism comprises a continuous casing or closure 2^a, preferably of a single casting and cylindric in cross-section, and a corresponding cylindric valve 2, also 35 preferably a single casting, having also preferably cylindric extensions 2^b, terminating in pistons or disks 2^c, fitting steam or air pressure tight within said casing or closure. Said valve-casing has at suitable or required intervals apart a number or plurality 40 of ports or orifices, the central one, 2^d, being for the steam or air pressure supply, the two nearest these, one on each side, 2^e, being the steam or air pressure inlet ports, those flanking the last-named, one also on each side, 2^f, being the exhaust-ports, and the remaining unferred-to ones, 2^g, being adapted for effecting connection with the condensing or water-spraying pipes, as presently seen.

45 Said ports are each preferably annular, being produced entirely around the valve-body, and rectangular in cross-section, the steam or air pressure supply port 2^d being adapted to provide for the connection therewith of a pipe 3, leading to a suitable steam or air pressure supply—as, for instance, a boiler or air-compressor. Within said valve-casing at its ends 55 are chambers 2^h to receive the pistons 2^c, and supplying steam or air pressure to said chambers and pistons are steam passages or channels 2ⁱ, communicating with said chambers and with the inlet-ports 2^e of the valve-casing 2^a via the passages 2^g, also produced in said casing and adapted to be alternately opened 60 and closed by the valve 2 to accordingly deliver and cut off the steam or air pressure to and from said pistons and their chambers.

Said valve-casing has also two converging passages 2^l, communicating with and forming continuations of the exhaust-ports 2^f and having a common outlet. The valve 2 also has at the required intervals apart for registration with the sundry ports of the valve-casing a corresponding number of ports 2^m 2ⁿ 2° 2^p, all except the valve 2^m being adapted to be alternately brought into coincidence with the ports of said valve-casing as said valve is reciprocated by the action of the steam or air pressure upon the pistons 2^c within the chambers 2^h, more fully seen presently. The central port 2^m is of a character, being elongated, to always register or be in communication with the central supply-port 2^d of the valve-casing 2^a as the valve 2 is shifted or reciprocated to establish communication between 85 said central supply-port and either of the inlet-ports 2^e of said valve-casing. There are two of each of the ports 2ⁿ 2^o 2^p, and they are adapted to establish communication alternately between the ports 2^e, 2^f, and 2^g of said valve-casing and the ports 1^a 1^b 1^c, respectively, the ports 1^a 1^b being produced in the walls of the water receiving or lifting chambers 1 1. The ports 1^a serve to supply the steam or air pressure to the water receiving or lifting chambers 1, the ports 1^b exhaust the steam or air pressure from said chambers after the cutting off said steam or air pressure supply, and the ports 1^c open up communication with pipes 5^a, delivering water in the form of spray into said chambers simultaneously with the exhausting action of the ports 1^b for aiding in producing a vacuum in said chambers. The exhaust-ports 2^f are each equipped with a hand-actuated valve 2^{ff}, 105 working in the valve-casing 2^a, which may be an end-tapered screw-threaded bolt to provide for regulating the exhaust, as will be readily understood. Connection or communication is effected between the ports 1^c, opening into the pipes 5^a, and the ports 2^g of the valve-casing 2^a, registering with the ports 2^p of the valve 2, by means of pipes 5^{aa}, suitably secured in place. Said pipes 5^{aa} are suitably equipped with hand-actuated valves or cocks 115 5^x to provide for regulating the amount of flow of water therethrough and accordingly the size or extent of the water-spray issuing from their nozzled ends. A valved by-pass channel 20 is produced in the valve-casing 2^a, establishing communication between the piston-chambers for supplying oil or air-pressure thereto in front of the pistons 2^c to provide for regulating the speed or movement of the valve 2 for the purpose already stated 125 above.

Having thus described my invention, what I claim as new, and desire to secure by Letters Patent, is—

1. In a pump of the character described, 130 the combination of a water-lifting chamber, means for supplying steam-pressure to said chamber, means for producing a vacuum in said chamber, means effecting the deliv-

ery of the water from said chamber, and a common means for effecting connection with said vacuum-producing and water-delivery means and for controlling said steam-pressure supply, comprising water pipes or passages and a valve controlling communication between said water pipes or passages and operatively connected to said steam-pressure-supply-controlling means, substantially as set forth.

2. In a pump of the character described, the combination of a water-lifting chamber, means for supplying steam-pressure to said chamber, means for the delivery of water from said chamber, valve mechanism for controlling said steam-pressure supply, means of connection between said water-delivery means and said valve mechanism, means for producing a vacuum within said water-lifting chamber, connecting with said valve mechanism, water pipes or passages connected with said water-delivery and vacuum-producing means and a valve controlling the communication between said water passages or pipes, substantially as described.

3. In a pump of the character described, the combination of a water-lifting chamber, means for supplying steam-pressure to said chamber, valve mechanism for controlling said steam-pressure supply to said chamber, pipe connection between said valve mechanism and the delivery-pipe of said water-lifting chamber, means for producing a water-spray in said chamber, connecting with said pipe connection, said valve mechanism controlling the communication between said water-delivery-pipe connection and said water-spray-producing means, substantially as described.

4. In a pump of the character described, the combination of a water-lifting chamber, means for supplying steam-pressure to said chamber and for controlling said supply, a water-delivery pipe for said chamber, a valved pipe connection between said steam-supply-controlling means and water-delivery pipe, and means for producing a vacuum in said chamber, connected up with said steam or air supply, said steam-supply-controlling means adapted to establish communication between said valve pipe connection and said vacuum-producing means, substantially as set forth.

5. In a pump of the character described, the combination of a water-lifting chamber, means for supplying and controlling steam-pressure to said chamber and for controlling said supply, a water-delivery pipe for said chamber, a pipe connection between said steam-pressure-supply means and said water-delivery pipe, and a lower-end perforated pipe connecting with said steam-pressure-supply-controlling means and depending in said chamber, said steam-supply-controlling means being adapted to establish communication between said pipe connection and said perforated pipe, substantially as set forth.

6. In a pump of the character described,

the combination of a water-lifting chamber, means for the delivery or discharge of the water of said chamber, means for producing a vacuum in said chamber, means supplying steam-pressure to said chamber, and for controlling said steam-pressure supply, means for effecting connection between said water-delivery and steam-pressure-controlling means, means for controlling communication with the means effecting connection between said water-delivery means and said steam-pressure-controlling means, means effecting connection between said vacuum-producing means and said steam-pressure-controlling means, and means for regulating the speed or action of said steam-pressure-controlling means, substantially as set forth.

7. In a pump of the character described, the combination of a water-lifting chamber, means for the delivery of the water of said chamber, means for supplying steam-pressure to said chamber, valve mechanism for controlling said steam-pressure supply, means for producing a vacuum in said chamber, means for effecting connection between said water-delivery means and said steam-pressure-controlling valve mechanism, means for controlling communication between said water-delivery means and said steam-pressure-controlling valve mechanism, and means for regulating the speed or action of said valve mechanism, substantially as set forth.

8. In a pump of the character described, the combination of a water-lifting chamber, means for supplying said chamber with steam-pressure, means for producing a vacuum in said chamber, valve mechanism for controlling said steam-pressure supply, and a supplemental valve for regulating the speed or action of said valve mechanism, substantially as set forth.

9. In a pump of the character described, the combination of a water-lifting chamber, means for supplying said chamber with steam-pressure, means for producing a vacuum in said chamber, valve mechanism for controlling said steam-pressure supply, and a supplemental valve connected up with said valve mechanism for regulating the speed or action thereof, substantially as set forth.

10. In a pump of the character described, the combination of a water-lifting chamber, means for supplying said chamber with steam-pressure, means for producing a vacuum in said chamber, valve mechanism for controlling said steam-pressure supply, and a supplemental valve connected up with said valve mechanism for regulating the speed or action thereof, said supplemental valve having a valved by-pass to deliver a resisting liquid in front of its piston or slide, substantially as set forth.

11. In a pump of the character described, the combination of a water-lifting chamber, means for supplying said chamber with steam-pressure, means for producing a vacuum in said chamber and valve mechanism compris-

ing a main valve and an additional valve, one adapted to control said steam-pressure and the other adapted to establish communication between the delivery-pipe of said 5 chamber and the vacuum-producing means, said valves being arranged on a common stem or rod, substantially as set forth.

12. In a pump of the character described, the combination of a water-lifting chamber, 10 means for supplying said chamber with steam-pressure, means for producing a vacuum in said chamber, and valve mechanism comprising a main valve and two additional valves, one adapted to control said steam-pressure 15 supply, one other adapted to establish communication between the delivery-pipe of said chamber and the vacuum-producing means, and a third one constituting the driving-valve, all of said valves being arranged on a common 20 stem or rod, substantially as set forth.

13. In a pump of the character described, the combination of a water-lifting chamber, 25 means for supplying said chamber with steam-pressure, a water-delivery pipe for said chamber having a branch pipe, a water-spraying pipe extending into said chamber, a valve mechanism comprising a driving-valve, and two additional valves, one adapted to establish 30 communication between said water-spraying pipe and said branch pipe, and the other controlling said steam-pressure supply, together with an additional water-lifting chamber, additional steam-pressure-supply means for the last-named water-lifting chamber, an 35 additional spraying-pipe extending into the same chamber, an additional branch pipe of said water-delivery pipe, communicating with the same valve as the first-referred-to branch pipe of said delivery-pipe is connected, substantially as set forth.

14. In a pump of the character described, the combination of a number of water-lifting chambers, duplicate steam-pressure-supply-controlling means therefor, water-delivery 45 pipes for said chambers, water-spraying pipes for said chambers, means for alternately establishing communication between said water-delivery pipes and said water-spraying pipes, and means for alternately controlling 50 said steam-pressure supply to said chambers, comprising a valve arranged to establish communication between said water-delivery pipes and said water-spraying pipe and operatively connected up with said steam-pressure-sup- 55 ply-controlling means, substantially as set forth.

15. In a pump of the character described, the combination of a water-lifting chamber, 60 means for supplying said chamber with steam-pressure, means for producing a vacuum in said chamber, valve mechanism comprising a casing or closure having a plurality of ports and a valve proper having a corresponding number of ports and arranged in said valve- 65 casing, adapted to effect communication between the delivery-pipe of said chamber and said vacuum-producing means, and said valve

mechanism also controlling a steam-pressure supply to said chamber, substantially as set forth.

16. In a pump of the character described, the combination of a water-lifting chamber, 75 means for supplying said chamber with steam-pressure, means for producing a vacuum in said chamber, valve mechanism comprising a casing or closure having a plurality of ports and a valve proper having a corresponding number of ports and pistons one at each end, and arranged in said valve-casing, adapted to effect communication between the delivery-pipe of said chamber and said vacuum-producing means, said valve mechanism also adapted to control the steam-pressure supply to said water-delivering chamber, substantially as set forth.

17. In a pump of the character described, the combination of a number of water-lifting chambers, water-delivery means for said chambers, water-spraying means for said chambers, and means for alternately controlling 90 the steam-pressure supply to said chambers and similarly establishing communication between said water-delivery means and water-spraying means, comprising a casing or chamber having a central steam-pressure-supply port, two inlet-ports for said chambers, two exhaust-ports connecting with said chambers and two other ports for said water-spraying means, and a valve proper having a corresponding number of ports, one adapted to 95 be continuously in communication with said supply-port, and its other ports adapted to alternately register with certain other of the valve-casing ports, and means for actuating said valve proper, substantially as set forth.

18. In a pump of the character described, the combination of a number of water-lifting chambers, water-delivery means for said chambers, water-spraying means for said chambers, and means for alternately controlling 100 the steam-pressure supply to said chambers and similarly establishing communication between said water-delivery means and water-spraying means, comprising a casing or chamber having a central steam-pressure-supply port, two inlet-ports for said chambers, two exhaust-ports connecting with said chambers and two other ports for said water-spraying means, and a valve proper having a corresponding number of ports, one adapted to 105 be continuously in communication with said supply-port, and its other ports adapted to alternately register with certain other of the valve-casing ports, said valve proper having 110 pistons at its ends contained in chambers of said valve-casing, and means for actuating said valve proper, substantially as set forth.

In testimony whereof I affix my signature in presence of two witnesses.

GEO. J. KENNEDY.

Witnesses:

M. A. GLESSNER,
AUG. W. BRADFORD.
